ATTORNEY

UNITED STATES PATENT OFFICE.

ANTON BEIFFOS, OF NEWARK, NEW JERSEY.

COLLAR-BUTTON CLASP.

Application filed January 6, 1928. Serial No. 244,922.

An object of this, my present invention, is the provision of means for sustaining a bow tie in tied condition and to afford the same with a spring actuated clamp to engage with the shank of a collar button for effectively sustaining the tie in proper position with respect to the collar of a wearer.

A further object is the provision of a device for this purpose, which shall be characterized 10 by simplicity in construction, ease in application and thorough efficiency in practical use.

To the attainment of the foregoing, the invention consists in the improvement as hereinafter described and definitely claimed.

In the drawing:—

Figure 1 is perspective view illustrating the application of my improvement, the button being separated from the clamp.

Figure 2 is an approximately centrally transverse sectional view through the improvement, the button being engaged by the clamp and locked on the tie.

Figure 3 is a sectional view approximately 25 on the line 3—3 of Figure 2.

Figure 4 is a perspective view, illustrating the manner in which the central fold or bow portion of a tie is engaged and fixed on one of the elements of the improvement.

Figure 5 is a plan view of a modified form of clamp.

While in the drawing I have illustrated my improvement applied and forming a fixed part of a bow tie, it is obvious that the same 35 may be attached to and provide a fixed element on a four-in-hand tie.

Referring now to the drawing, the numeral 1 designates a tie folded in the usual manner to form what is known as a bow tie. The 40 strip 2, that comprises the central or bow portion of a tie, is folded therearound, the ends of said strip being disposed over the back of a tie and need not meet. The ends of the portion 2 have forced therethrough spaced teeth 3 formed on the opposite edges of the central and rectangular portion 5 of the clamping or sustaining member of the improvement. The member 5 is formed of a thin strip of bendable metal, and has its 45 corners provided with right angularly disposed bendable strip extensions 6—6 and 7—7. The strips 7 are of a less length band than the strips 6. The said strips 7 are designed to be bent over the ends of the fold 2 55 of the collar 1 which are impinged by the teeth 3, and as a matter of fact they lie in close proximity to the inner edges of such teeth.

Between the bendable strips or fingers 7, the plate 5 is formed with other outwardly extending bendable strips or fingers 8—8.

Designed to be arranged against the outer face of a plate 5, or rather against the bent fingers 7 on the said plate, there is the inner and closed face of a substantially rectangular metal casing 9.

Preferably the outer face of a casing 9 is open, but this casing is closed by a cover plate 10, and the rear casing may be formed or provided with bendable fingers 11, designed to be arranged transversely of the center thereof and to be bent against the closure plate 10. In addition to this, the fingers 6—6 and 8—8 on the plate 5 are bent over the top, bottom and sides of the casing 9 and likewise bent over the outer face of the plate 10, for effectively holding the said plate in casing closing position.

One of the lower fingers 11 may be centrally slotted longitudinally and transversely, and the metal bounded by these strips bent into the casing and rounded to form an eye 12 to which is connected the lower and looped portion 13 that is centrally formed on a longitudinally extending rod 14. The ends of the 85 rod 14 are bent and extended to provide the same with substantially rectangular portions, whose inner and confronting arms are vertically disposed in the casing when the device is in operative position, and which arms 90 are indicated for distinction by the numerals 15, the lower ends of the arms 15 are extended outwardly and pass through openings in the sides of the casing. These portions, indicated by the characters 16, are bent upon 95 themselves to form the same with outer substantially U-shaped finger push portions 17. The arms 15 provide a pair of clamping jaws, and are held in spaced relation by contact elements 18 which engage with the outer arms 100 of the rectangular portions of the rods 14.

The contact elements 18 are preferably formed by slitting and bending inwardly parts of the metal cover plate 10, and the said cover plate, between and below these strips 105 18, has a transverse slot 19 therethrough. The slot 19 is designed to receive therein the shank 20 of a collar button 21, and the edges of the said shank are notched as at 22 for engagement with the jaws 15. Obviously 110 the pressure upon the end 17 of a clamp will move the jaws away from each other to per-

mit of the removal of a collar button from engagement with the neck tie.

In Figure 5 I have shown a clamp member slightly different in construction from that previously described. This clamp includes a substantially rectangular body 5' formed at its corners with right angularly extending bendable fingers 6' and 7'. The fingers 7' are of a less length than the fingers 6' and the said fingers 7' are designed to be bent over the ends of the bow portion of a tie when the latter is arranged against the flat body 5', while the fingers 6' are designed to be bent over and to clamp the plate 5' on the substantially rectangular casing 9.

Also while I have stated that the casing may be integrally formed with fingers to engage the outer or face plate thereof, such fingers are not an absolute requirement as the fingers 6 and 8 of the plate 5, or the fingers 6' of the plate 5' when brought to engagement with such face plate will effectively hold the same on the casing. Also, and as disclosed by the drawings the ends 25 of the U-shaped fingers 17 that are received through the openings in the sides of the casing are bent or hooked, as at 25, to contact with the inner walls of the said casing and limit the outward movement of the push portions 17 therethrough.

While it is believed that the foregoing description, when read in connection with the accompanying drawing, will fully set forth the construction, operation and advantages 35 of my improved device, obviously I do not wish to be restricted to the precise details of construction herein set forth, and therefore hold myself entitled to make such changes therefrom as fairly fall within the scope of 40 what I claim.

Having thus described the invention, I claim:—

1. In a device of the character set forth, and in combination with a collar button having a flat shank whose edges are notched, of a plate having its edges formed with teeth and its corners provided with bendable finger extensions, and the teeth of the said plate designed for impinging engagement with the bow portion of a neck tie, and certain of the 45 fingers designed to be bent over the plate against the impinged ends of the tie, a casing resting against the said bent fingers having an outer closure plate designed to be en-

gaged by the remaining fingers of the first mentioned plate when the latter are bent over the casing and against the closure plate, a rod having an adherent resiliency which is centrally secured in the casing and which is bent upon itself to provide substantially rectangular portions, whose inner arms form spring jaws, stop elements carried by the closure plate for engaging the outer arms of said rectangular portions of the rod, the bow arms of the rods having their ends projected and extended through the ends of the casing and bent upon themselves to provide substantially U-shaped finger grips, and the closure plate having an opening therethrough opposite the jaw portions of the rod for the passage of a shank of a collar button therethrough.

2. In a device of the character set forth, and in combination with a collar button having a flat shank whose edges are notched, of a plate having its edges formed with teeth and its corners provided with bendable finger extensions, and the teeth of the said plate designed for impinging engagement with the bow portion of a neck tie, and certain of the fingers designed to be bent over the plate against the impinged ends of the tie, a casing resting against the said bent fingers having an outer closure plate designed to be engaged by the remaining fingers of the first mentioned plate when the latter are bent over the casing and against the closure plate, a rod having an adherent resiliency which is centrally secured in the casing and which is bent upon itself to provide substantially rectangular portions whose inner arms form spring jaws, stop elements carried by the closure plate for engaging the outer arms of the said rectangular portions of the rod, the bow arms of the rods having their ends projected and extended through the ends of the casing and bent upon themselves to provide substantially U-shaped finger grips, the closure plate having an opening therethrough opposite the jaw portions of the rod for the passage of a shank of a collar button therethrough, and bendable fingers carried by the casing for also engaging with the closure plate.

In testimony whereof I affix my signature.

ANTON BEIFFOS.
